SKI POLE HANDLE

Melville A. Miller, W. County Line Road,
Barrington, Ill.

Filed May 4, 1962, Ser. No. 69,967

Term of patent 14 years

(Cl. D34—14)

Fig. 2.

Fig. 1.

Fig. 3.

Fig. 4.

Fig. 5.

FIGURE 1 is a front elevational view of a ski pole handle embodying the features of my new design with a wrist strap shown in broken lines for illustrative purposes only;

FIGURE 2 is a side elevational view of the lefthand side of the handle means viewed in FIGURE 1;

FIGURE 3 is a side elevational view of the righthand side of the handle means viewed in FIGURE 1;

FIGURE 4 is a top plan view thereof;

FIGURE 5 is a cross-sectional view taken substantially at line 5—5 of FIGURE 1 and looking in the direction of the arrows thereon.

I claim:

The ornamental design for ski pole handle, substantially as shown and described.
